Fig. 3

Fig. 4

Fig. 5

Fig. 6

Fig. 7

Fig. 8

Fig. 9

Fig. 11

FIG. 1 is a perspective view of an adjustable safety razor cartridge showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof;

FIG. 7 is a front elevational view of a modified form of an adjustable safety razor cartridge showing my new design;

FIG. 8 is a rear elevational view of the embodiment of FIG. 7;

FIG. 9 is a top plan view of the embodiment of FIG. 7;

FIG. 10 is a bottom plan view of the embodiment of FIG. 7; and

FIG. 11 is a side elevational view of the embodiment of FIG. 7.

The not shown side elevational views of the embodiments of FIGS. 1 and 7 are mirror images of FIGS. 6 and 11, respectively.

This application is a continuation-in-part of application Ser. No. 526,081, filed Nov. 22, 1974, now abandoned.

I claim:

The ornamental design for an adjustable safety razor cartridge, as shown and described.
